UNITED STATES PATENT OFFICE.

HUGH W. IVEY, OF BLOOMSBURG, PENNSYLVANIA.

CLOTHES-LINE PROP.

1,063,801.

Specification of Letters Patent.

Patented June 3, 1913.

Application filed August 29, 1912. Serial No. 717,772.

To all whom it may concern:

Be it known that I, HUGH W. IVEY, a citizen of the United States, residing at Bloomsburg, in the county of Columbia and 5 State of Pennsylvania, have invented certain new and useful Improvements in Clothes-Line Props, of which the following is a specification.

The invention relates to clothes props and 10 has for its object the provision of a prop comprising a pole provided with a plurality of transverse slots arranged in vertical series, said slots being adapted to receive the clothes line and providing for accommodat- 15 ing the prop to the height of clothes line to which it is to be attached, said pole having a rod slidably mounted thereon and adapted to prevent the clothes line from be- 20 ing disengaged from the slot in which mounted.

My invention will be described in detail hereinafter and illustrated in the accompanying drawings, in which—

Figure 1 is a front view in elevation of 25 my improved clothes prop; Fig. 2, a side view partly broken away showing the rod lowered to permit of inserting the clothes line in the uppermost cross slot; and Fig. 3, a detail view in perspective of the rod.

30 In the drawings similar reference characters will be used to designate corresponding parts throughout the several views.

My improved clothes prop comprises a pole 1 having a plurality of slots 2 therein 35 that extend transversely of one face of said pole and as shown in Fig. 2 inclined downwardly from said face. Slidably mounted on the pole 1 is a rod 3, said rod being mounted in staples or other suitable fasten- 40 ings 4 secured to said pole intermediate of the slots 2 and below the lowermost slot. The rod 3 has its lower end formed with a circular loop 5 that is bent to extend laterally of the main portion of the rod as shown 45 and is adapted to seat in a notch 6 formed in one of the front corners of the post to hold said rod in position to prevent accidental removal of the rope from any one of the slots 2.

In use it will be apparent that when it is 50 desired to insert the clothes line in one of the slots 2, the rod 3 is given a quarter turn to move the loop 5 out of engagement with the notch 6 and the rod moved downwardly to expose the slot in which it is desired to 55 insert the rope. After insertion of the rope, the rod is returned to its original position and the loop 5 moved into the notch 6 to retain the rod in position to prevent accidental removal of the clothes line from the 60 slot.

The slots 2 in addition to providing for arranging the prop to conform to the height of the clothes line also provide for the use of 65 the prop with two or more clothes lines ar- ranged one above the other as will be clearly apparent.

Having thus described my invention what I claim is:—

1. A clothes prop comprising a pole hav- 70 ing a plurality of transverse slots in one of its faces, said slots inclined downwardly from the face of said pole, a rod slidably mounted on the pole and adapted to close the entrance to said slots, said rod having 75 its lower end formed with a laterally ex- tending loop, and means associated with said pole to engage said loop to hold the rod in locking position.

2. A clothes line prop comprising a pole 80 having a plurality of transverse slots in one of its faces, said slots inclined downwardly from the face of said pole, a rod slidably mounted on the pole and adapted to close the entrance to said slots, said rod having 85 its lower end formed with a laterally extend- ing loop, and the pole provided with a trans- verse notch adapted to engage said loop to hold the rod in the position to close said slots. 90

In testimony whereof I affix my signature in presence of two witnesses.

HUGH W. IVEY.
